United States Patent Office

Des. 227,550
Patented July 3, 1973

227,550

HOLDER OR THE LIKE FOR DRAINERS ON PAILS AND OTHER ARTICLES

Thomas P. O'Donnell, 220 Highland Blvd.,
Brooklyn, N.Y. 11207

Filed Sept. 1, 1971, Ser. No. 177,209

Term of patent 14 years

Int. Cl. D8—08

U.S. Cl. D8—246

Fig. 1.

Fig. 2.

FIG. 1 shows a perspective view of said invention of a holder or the like for drainers on pails and other articles.

FIG. 2 shows a perspective view thereof in an upside-down position, being taken from the side opposite that in FIG. 1.

I claim:

The ornamental design for a holder or the like for drainers on pails and other articles, as shown.
